JULIUS VON WLADKOWSKY, OF NEW YORK, N. Y., ASSIGNOR TO S.-P. VAPORIZER CO., OF NEW YORK, N. Y., A CORPORATION OF NEW YORK.

GASEOUS-FUEL MIXER.

1,254,102.

Specification of Letters Patent. Patented Jan. 22, 1918.

Application filed June 13, 1914. Serial No. 844,912.

To all whom it may concern:

Be it known that I, JULIUS VON WLADKOWSKY, a subject of the Emperor of Austria, and a resident of the city of New York, borough of Manhattan, in the county and State of New York, have invented a new and Improved Gaseous-Fuel Mixer, of which the following is a full, clear, and exact description.

10 My invention relates to a device designed to prevent backfiring through the carbureter of an internal combustion engine. An object of the invention is to improve the construction of a device of this character so it will be more reliable and efficient in use, inexpensive to manufacture, and so designed that it can be readily applied as an attachment to carbureters already in use. Another object of the invention is to provide 15 a mixer which by its novel construction has the additional functions of causing a better mixture of fuel and air and reducing fuel consumption. I attain the above objects by means screening the mixing conduit of the engine, which screening means are adapted to carry porous material and which material will arrest liquid particles of fuel and vaporize the same and, therefore, greatly facilitate the evaporation of the fuel in the 20 mixing conduit, which will necessarily facilitate the starting of the engine.

In the accompanying drawings one embodiment of my invention is illustrated, and similar reference characters are employed 25 to designate corresponding parts in the several views in which—

Figure 1 is a side view of a carbureter and engine manifold with portions broken away to show the anti-backfiring and fuel-saving attachment in position;

Fig. 2 is a plan view of the attachment before the lead gasket is die cast about it;

Fig. 3 is a section on line 3—3, Fig. 4;

Fig. 4 is a plan view of the attachment 45 complete; and

Fig. 5 is a fragmentary view of a modified structure of the gasket before the same is connected to the screen.

Referring to the drawings, 5 designates 50 a carbureter which is connected with a

manifold 6 of a gas engine, there being at the point of connection an anti-backfiring attachment 7. This attachment is formed of two superposing screens 8 and 9, preferably of copper-wire netting. The upper 55 screen is in the shape of a dish the central portion of the bottom of which is depressed outwardly and forms a seat for porous material 10 which is maintained in place by the second or lower screen 9, which is a segment 60 of a sphere and which engages the upper screen 8 with its convex side, the lower screen 9 being spaced from the bottom of the upper screen 8 by flanges 11 of the screen 8. The two screens, which are stamped out 65 by means of a die, are bound together by a suitable metallic ring 12, which is U-shaped in cross section. The so-bound screens form a container in which is positioned porous material and which container 70 is then placed into a mold and a gasket 13 of any suitable metal is die cast about it. This gasket has, preferably, raised annular portions 14 adjacent the screens, as indicated in Figs. 3 and 4, which form a packing 75 to effectively seal the joints between the carbureter and the manifold.

The anti-backfiring attachment is preferably so placed between the carbureter and manifold that the screen 8 engages the manifold; and the diameter of the screen 8 is such as to fit snugly into the manifold. This provision makes the device self-centering. The gasket 13, which is in the shape of a flange and forms the support for the 85 screens, can also be formed by a different method, by casting the flange 13 in a suitable material with an annular flange 15 (shown in Fig. 5) perpendicular to the flange 13' and bent downwardly and parallelly to flange 13' after the screens are inserted therein. In case of a backfire, the two superposed screens will positively prevent the passage of the flames beyond the lower screen 9 no matter what the force of 90 the backfire is. The porous material 10, which is preferably mineral wool or asbestos, or a mixture thereof with cotton, will absorb vapor or particles of liquid fuel passing through the carbureter and the mani- 100

fold and vaporize them, thereby increasing the efficiency of the carbureter, and also diminish the consumption of fuel. Furthermore, this provision of the absorbing matter within the manifold minimizes the engine troubles, which are generally due to the fact that liquid fuel enters into the cylinder and the mixture is enriched unnecessarily at an inappropriate moment, reducing the efficiency of the engine and causing an increase of fuel consumption.

From the foregoing description, taken in connection with the accompanying drawings, the advantage of the construction and method of operation of the device shown will be readily understood by those skilled in the art to which the invention pertains, and while I have described the principle of operation, together with the device and method of making the same, which I now consider to be the best embodiment thereof, I desire to have it understood that the device shown is merely illustrative and that such changes may be made when desired as are within the scope of the appended claims.

The margins of the two screens are superimposed and held firmly in place against the back-firing strains by the compressible metal gasket, and the absorbent ball centrally placed between the screens forms a spacer between the screen centers that keeps them spaced apart as is necessary for satisfactory practical results.

The ball or wad 10 of porous or absorbent material performs the double function of absorbing gaseous mixture and of holding the upper and under screens firmly spaced apart to resist the pressure of backfiring, which would otherwise tend to, and often would in fact, force the upper screen down into direct contact with, or close enough to, the under screen to permit backfiring. The cross-sectional area of the ball or wad 10, which is located between the central portions of the opposed and separated screens 8 and 9, is very considerably less than the area of the central opening of the gasket, or in other words of the screens considered as mere horizontal members, and by far the greater portion of the screen area in their portions encircling the ball or wad 10 and lying within the central opening of the gasket, is entirely unobstructed and permits the flow from the carbureter to the manifold of that large and constant volume of gaseous material which is necessary for effective operation of the engine. As viewed in plan in Fig. 4 the diameter of the central opening of the gasket which is spanned by the screens 8 and 9 is approximately 1 $\frac{1}{2}$ inches, while the diameter of the central absorbent spacer 10 is approximately a little less than $\frac{1}{2}$ of an inch. The area of the central obstruction at 10 to the flow of gaseous mixture is therefore very

much less than the unobstructed screened area around the obstruction at 10 and within the central opening of the gasket, and this is a very material and important matter for the practical operation of a device of this character when and if it is provided with a central spacer such as 10 for holding the screen sufficiently separated to prevent backfiring. Both screens 8 and 9 are concavo-convex with their concavities upward, forming an arching structure that also is highly resistant to the backfiring pressure when it occurs.

The upper and under shoulders 14 of the gasket encircling the central screened opening of the gasket also perform a double function. They afford a sufficient amount of compressible metal or other suitable gasket-forming material solidly and strongly to anchor the superimposed margins of the screens 8 and 9 in place in the gasket, and they also permit the manifold flange 16 and carbureter flange 17 when they are drawn together by the bolts 18 through the flanges and through the bolt holes 19 in the oppositely-extending wings 20 of the gasket, to crush them down as shown in Fig. 1, whereby the metal in the shoulders conforms to surface inequalities of the flanges and produces a gas-tight joint which prevents escape of gaseous mixture on its way to the carbureter and also prevents escape of vapors from the manifold in case of backfiring. It will be observed that the wings 20 which are diametrically opposite one another are thinner outwardly of the shoulders 14 than are the shoulders; and this construction of the gasket is practically of very great importance for the practical operation of the device. The wings with the bolt-holes through them are of a shape to be received between the flanges of the bolt-holes or preferably elongated in the direction of the length of the wings, so that the attachment can be readily fitted between the flanges 16 and 17 and firmly clamped in place with the shoulders 14 crushed and deformed into a tight fit with the inequalities of the contacting surfaces of the flanges. At the same time the metal or material of the shoulders 14 is forced more firmly by the deformation upon the margins of the screens, whereby the screens themselves are bodily much more effectively clamped in position to resist the very great force that sometimes occurs in backfiring, and that when only one screen is used frequently disrupts the screen with all the disastrous consequences attendant upon backfiring. Two screens are essential to prevention of backfiring, and more than two screens are unnecessary, but the two screens must be constructed and held sufficiently far apart to withstand backfiring pressures.

The mode of operation of this device in

respect to vaporization appears to be as follows: The stream of gasolene coming from a nozzle in the carbureter strikes against the double screen, initially against the under screen, and fills the apertures of the screen mesh with exceedingly thin layers of liquid gasolene. These thin layers of gasolene are held in each separate aperture by capillary attraction to the wire comprising the mesh, and are constantly subject to surface tension which produces a rapid volatilization of the gasolene. Gasolene will volatilize owing to surface tension no matter how thick the layer of gasolene is; say for instance in an open vessel. But the surface tension and constant volatilization is in inverse proportion to the thickness of the layer and the thinner the layer the more rapid volatilization. As the air strikes these thin layers of gasolene which from the surface tension are in a continuous state of volatilization, the latter increases and a very intimate gaseous mixture of gasolene and air enters the cylinders where it is exploded. Without the device the gasolene in its liquid state in the form of spray is carried by the air into the cylinders in a quantity far in excess of that which is necessary to produce the explosive mixture, and thereby a lot of gasolene is unnecessarily wasted without taking an efficient part in the explosion, and this waste results in carbonization.

Such is the explanation of the considerable economy in gas shown by the application of this device. The action of the cotton or absorbent ball seems to consist in its being saturated with gasolene and thereby providing at the device an atmosphere saturated with gasolene vapor that facilitates starting and re-starting.

Having thus described my invention, I claim as new and desire to secure by Letters Patent:

1. A gaseous fuel mixer comprising a dish-shaped screen, a second screen forming a segment of a sphere associated with said first screen, said second screen engaging the dish-shaped screen with its convex part, porous material between the central parts of said screens, said dish-shaped screen having a central depressed portion forming a seat for the porous material, a ring connecting the two screens together, whereby the second screen maintains the porous material in its seat, and whereby said screens form a gauze container, and a support for said container engaging said ring, said support forming a gasket.

2. As an article of manufacture, a gauze fuel mixer comprising a gasket plate having a central opening and an annular seat at the opening, a gauze container formed of two sections having marginal flanges, a ring positioned in the seat of the gasket plate and

engaging the flanges of the sections of the container, and porous material in the central portion of the container adapted to leave an annular space about the porous material in the said container.

3. The combination of a pair of screens the margins of which are superimposed with a compressible metallic gasket which holds the superimposed margins together; the screens being elsewhere spaced apart; and a spacer located centrally between the screens and held in place by the pressure of the screens on opposed portions of the spacer, the spacer keeping the screens separated except at their said margins; said gasket having an opening spanned by the separated screens, the greater area of the screens being unobstructed around the central spacer and within the wall of the central opening, the upper screen rising upwardly away from the under screen, and the spacer serving to hold the screens separated.

4. A structure as specified in claim 3, in which the screens are severally concavo-convex and mounted with their convex walls upward.

5. A structure as specified in claim 3, in which the gasket wall inclosing the screened opening of the gasket is formed with deformable gas-tight-joint-forming annular shoulders.

6. A structure as specified in claim 3, in which the gasket is formed with wings extending away from the shoulders, the wings being thinner than the shoulders and severally provided with a bolt hole.

7. The combination of the flange of an internal-combustion engine's intake-conduit and a flange of a carbureter delivery-conduit with an intermediate gasket having an opening connecting the conduits, and compressible annular shoulders on both its sides surrounding such opening, the shouldered portion of the gasket being thicker than the remaining portions of the gasket; a pair of screens anchored in such shouldered portion of the gasket; and a spacer separating the central portions of the two screens, the screens being elsewhere separated one from another; and clamping devices for deforming said shoulders and forming gas-tight joints between the gasket and the flanges, and clamping the flanges and gasket firmly together.

8. A gaseous fuel mixer comprising a dish-shaped screen; a second screen forming a segment of a sphere, associated with said first screen, said second screen engaging the dish-shaped screen with its margin; porous material between the central parts of said screens; and a gasket for said container, the upwardly projecting side of which is vertical and annular and rises

away from the second screen whereby the dish-shaped screen and the second screen are spaced apart in the horizontal direction for effective resistance to backfiring and for 5 accommodation in the chamber of the container of the centrally located porous material.

In testimony whereof I have signed my name to this specification in the presence of two subscribing witnesses.
